CANDLE LIGHTER AND EXTINGUISHER

Harrison Van Horn, Mount Vernon, N. Y.

Application January 9, 1939, Serial No. 249,936

2 Claims. (Cl. 67—6)

This invention relates to candle lighters and extinguishers and has for an object to provide an improved construction wherein a taper may be manipulated properly for lighting candles in more or less inaccessible places and out of ordinary reach and, at the same time, present means whereby the taper or wick may be fed forward from time to time as it is consumed.

Another object of the invention is to provide an improved candle lighter and extinguishing device wherein a supporting tube is used which acts as a support for a taper and as means for directing air to a desired point for blowing out a candle.

A further object, more specifically, is to provide a candle lighter and extinguisher wherein a jointed tubular structure is provided having a collapsible bulb at one end and a nozzle at the other bent at an angle to the general direction of the tube.

In the accompanying drawing—

Fig. 1 is a side view of a combined candle lighter and extinguisher disclosing an embodiment of the invention;

Fig. 1a is a side elevation of one of the sections shown in Fig. 1;

Fig. 2 is a longitudinal vertical sectional view through the lower part of the structure shown in Fig. 1 and illustrating how the collapsible bulb is connected to the handle;

Fig. 3 is a vertical sectional view through the upper part of the structure shown in Fig. 1, the same being on an enlarged scale and illustrated in a position for blowing out the flame of a candle;

Fig. 4 is a perspective view of the air nozzle and lip shown in Fig. 3;

Fig. 5 is an enlarged perspective view of the upper part of Fig. 1a;

Fig. 6 is a view of the upper part of the extinguishing tube disclosing a modified form of the invention;

Fig. 7 is a perspective view of the removable nozzle shown in Fig. 6; and

Fig. 8 is a perspective view of the ring and lip illustrated in Fig. 6.

In many places where candles are used it is often found that the flame of the candle is at a point which is more or less inaccessible or out of reach of an average size person. In order to take care of a situation like this candle lighters utilizing tapers and also snuffing devices or other means for putting out the flame of the candles have been used. In churches where candles are used, sometimes the flame is five or six feet above the head of a man and access to the flame is

very difficult by reason of its high position. In the present invention means have been provided whereby a high candle may be readily lit and also readily put out. As shown in Fig. 3 of the accompanying drawing, 4 indicates a candle of any desired kind, which when lit provides a flame 2. A metal cap or head 3 is sometimes used on the candle though this is not essential to the present invention but is very desirable. As shown in Fig. 1, the tube 4 is adapted to receive air from a collapsible bulb 5 and direct the air out a nozzle 6, as shown in Fig. 3, in order to extinguish the flame 2. A tubular holder or taper support 7 is secured by straps 8 to the tube 4, as illustrated particularly in Figs. 1 and 3, and this holder is provided with a bend 9, whereby a lateral extension 10 is presented through which the taper 11 projects. This extension is cut away at 13 so as to expose a section of the taper sufficiently long to be grasped by the thumb and finger of a person, whereby the taper may be moved back and forth through the tubular support 7. By this arrangement any wax on the taper cannot enter the tubular holder or support, and the taper is pulled rather than pushed through the support. 25 When the taper has been completely consumed or becomes too short for use, a new taper is preferably inserted from the bottom of the tubular support 7 and forced upwardly until it appears in the position shown in Fig. 3. After the taper 30 has moved to the position shown in Fig. 3, it may be moved by grasping the section 14 with the fingers and thumb. The tube 4 at the lower end is surrounded by a handle 15 which may be wood or other material and which is provided with an 35 annular groove 16 for receiving the bead 17 of the bulb 5, whereby the bulb is held in place. This bulb may be of any desired structure, as for instance an ordinary rubber bulb, which will automatically distend itself after being released. 40 When the bulb 5 is quickly collapsed air will be propelled with some considerable pressure through pipe 4 and be discharged out the nozzle 6, as indicated by the arrows 18 in Fig. 3. The nozzle 6 is flattened, as shown in Fig. 4, and is 45 provided with a lip 19 which readily fits over the upper end of the cap 3 to steady the tube 4 when the same is being used as an extinguisher. If the cap 3 should not be in place the nozzle 6 is placed in substantially the position shown in Fig. 50 3 and then the bulb 5 collapsed. This will blow out the flame 2 and leave the wick of the candle standing upright. This is advantageous as it permits the ignited taper 12 to readily ignite the wick of candle 1, and then as the wick of candle 55

1 is ignited it will produce the desired shape flame, as shown in Fig. 3, because of its upright position. Where snuffers are used, the wick is bent over and sometimes some of the melted wax 5 runs over the candle and even drops down on objects below. By providing means for blowing out the flame, the wick of the candle is left upright. This obviates any flow of the melted wax and also leaves the wick in good shape for being 10 ignited the next time the candle is ignited.

The tube 4 is preferably made in sections and is preferably formed of aluminum so as to be very light even though the structure, as illustrated in Fig. 1, is intended to be approximately ten feet 15 long. There are disclosed three sections but preferably each of these sections is three feet or more in length. Section 4" is illustrated in Figs. 1a and 5. From these figures it will be seen that sections 4' and 4" are provided with a tubular 20 connecting member 20, which may be permanently secured in section 4" with a projecting portion 21 having a slit 22 extending from the end of the section 4". A sleeve 23 is shrunk on to the section 4", or otherwise secured thereto, so that the lower end of section 4''' may readily fit over the extension 21 and into the sleeve 23, whereby the parts are properly aligned and held against accidental escapement. Section 4' at the upper 25 end is made similar to that shown in Fig. 5 and 30 coacts with the section 4". The top section 4''' is provided with a nozzle 6, while the lower end merely fits into the sleeve 23.

In Figs. 6 to 8 inclusive, a slightly modified form of nozzle is presented. In this form of the 35 invention, the top section 4''' is cut off straight and the end 24 of the nozzle 25 is slid therein. The end 24 is provided with a notch 26 so that it may be slightly contracted as it starts into the section 4'''. A bead 27 is provided at the upper 40 portion of the end 24 and a ring 28 is clamped against the end of the section 4''' by said ring. The ring 28 is provided with an extension or lip 45 29 that acts as a lip similar to lip 19. The outer end or top of the nozzle 25 is provided with a round closing portion 30 having a diagonal slit 31 arranged therein. When this form of the invention is used, the lip 29 is placed in the position shown in Fig. 3 and when the bulb 5 is collapsed air will rush through the tube 4 and through 50 the slit 31 for extinguishing the flame 2.

When the device is to be used on candles which are on a level with the head of a person or slightly above or below the same, the central section 4" may be removed and the top section 4''' fitted on to the section 4' in order to make a shorter 5 lighter. Preferably the handle 15 is held in place by friction and, if desired, this handle should be applied directly to the lower end of section 4''', whereupon there may be produced a candle lighter and extinguisher approximately three 10 feet long which would answer certain requirements. It will, therefore, be seen that by reason of the construction provided low candles may be lighted and extinguished and candles that are placed high in the air may be lighted and extinguished without injury to the candle or to any of the surrounding furniture.

I claim:

1. A candle lighter and extinguisher of the character described comprising a tubular member, means at one end of the tubular member for supplying air under pressure to the interior of the tubular member, a flattened nozzle at the opposite end of the tubular member for directing air in a sheet to the desired zone and a curved 25 lip forming part of the nozzle extending from the discharge end of the nozzle and adapted to steady the tubular member when the discharge end of the nozzle is arranged opposite a flame, whereby the air passing through the tubular member may be directed in a sheet toward the flame in a plane substantially at right angles to the axis of the flame.

2. A candle extinguishing device including a tubular body, a handle at one end of said body, 35 a rubber collapsing bulb carried by said handle in position to force air under pressure into the tubular body when collapsed, said body at the end opposite the bulb being provided with a nozzle having a flat opening extending at an angle to the 40 general direction of the body for discharging the air in a sheet, and a substantially hook-shaped lip for steadyng the end of the body when the nozzle is positioned adjacent a flame, said lip also functioning to hold the discharge end of 45 the nozzle so that the air from the nozzle will move in a plane at right angles to the axis of the flame.

HARRISON VAN HORN.
